United States Patent Office.

AARON GUINZBURG, OF BOSTON, MASSACHUSETTS.

Letters Patent No. 91,227, dated June 15, 1869.

IMPROVED HOUSEHOLD-IMPLEMENT.

The Schedule referred to in these Letters Patent and making part of the same.

To all whom it may concern:

Be it known that I, AARON GUINZBURG, of Boston, in the county of Suffolk, and Commonwealth of Massachusetts, have invented a new and improved Household-Implement; and I do hereby declare that the following is a full and exact description thereof, reference being had to the accompanying drawings, and to the letters of reference marked thereon.

My invention consists of a metallic implement for household-use, and adapted by its form, as shown in the drawings, to various purposes.

The accompanying drawing represents the implement in an inverted position.

The wedge-shaped points B B B B, of varying widths, are designed to lift stove-covers of varying sizes.

The slots in two of said points c c are to adapt those points to the purpose of drawing tacks.

The square holes A A A A, of varying sizes, are intended to adapt the implement, as a wrench, to various-sized stove-grate bars, for the purpose of shaking

and turning such grates, and are very convenient and useful as wrenches for other purposes, such as about gas-meters, water-pipes, &c.

The implement, when placed in a position the reverse of that shown in the drawings, and resting upon the points B B B B, is a very safe and convenient support for hot flat-irons, coffee-pots, and other household-utensils.

It is cheap, compact, and combines the advantages above described in one instrument, whereas they are usually attained only by means of several implements, and is, therefore, more readily at hand.

What I claim as my invention, and desire to secure by Letters Patent, is—

The metallic implement as herein described, with its wedge-formed points B B B B, slots O C, and holes A A A A, as shown, for the purpose described.

AARON GUINZBURG.
